UNITED STATES PATENT OFFICE

2,562,619

WINDOW PLATFORM

John Kolodziej, Chicago, Ill.

Application November 3, 1947, Serial No. 783,817

1 Claim. (Cl. 304—24)

1

The present invention relates to window platforms, and has for its main object the provision of a platform engageable to the window sill, and which may be disposed outwardly of the window for providing a support upon which a person may either sit or stand while washing window panes.

A still further object of the present invention is the provision in a window platform of the character indicated of adjustable means whereby the platform may be affixed to sills of various widths.

With the above general objects in view and others that will appear as the invention is better understood, the same consists in the novel construction, combination and arrangement of parts hereinafter more fully described, illustrated in the accompanying drawing and pointed out in the appended claim.

In the drawing forming a part of this application and in which like designating characters refer to corresponding parts throughout the several views:

Fig. 1 is a side elevational view of the present invention in an operative association with a window sill, the latter shown in a transverse cross-section;

Fig. 2 is a front elevational view thereof; and
Fig. 3 is a top elevational view thereof.

Referring to the present drawing in detail, there is shown therein a window platform which includes a pair of spaced cylindrical bars 10, the outer, free ends of which are threaded as at 11. In an operative association of the window platform with a window said bars 10 overlie sill 12, including ledge 13 integrally formed with said sill 12 and projecting inwardly of a dwelling. Said sill and ledge 13 rest upon dwelling wall 14. Outwardly said sill 12 and wall 14 define right angled corner 15.

The opposite ends of said bars 10 are bent into an upward direction, at an obtuse angle with relation to the body portions of said bars 10, and effect sides 16.

Back 17 is formed out of a U-shaped member, including vertical members 18, to the upper ends of which the upper ends of sides 16 are connected in a rigid relation by welding or any other suitable means. Each of said vertical members 18 is horizontally bent, towards said bars 10 and at right angles with relation to said vertical members 18, for defining a pair of supporting arms 19 for supporting thereon board 20 or any other similar support upon which a person can stand or sit. The front ends of said arms 19 are bent into an upright direction and at right angles with relation to said arms 19, for defining a pair of

extensions 21. Said extensions 21 and the adjacent portions of arms 19 fit within corner 15 in an operative association of the platform with a window. Said arms 19 are on a plane below the plane of said bars 10. The upper ends of said extensions 21 are rigidly connected, by welding or otherwise, as at 22, to the ends of said bars 10 and adjacent the lower ends of said sides 16.

Mounted upon bars 10 for free shifting movement longitudinally thereof are U-shaped clamping members 23, each of which includes upper tubular portion 24 which is freely slidable upon each bar 10. Angle member 25, by its horizontal portion is superimposed upon the lower free end 15 of each of said clamping members 23 and is welded or otherwise rigidly affixed to the inner face of each of said clamping members 23, as is clearly seen in Fig. 1. By virtue of this arrangement angle member 25 rigidly connects a pair of said clamping member 23, and when tubular portions 24 thereof have been inserted upon two bars 10 said clamping members 23 and angle member 25 are adapted for bodily shifting movement upon said bars 10.

25 Wing nuts 26 engage threads 11 upon bars 10. Brace 27 connecting vertical members 18 for maintaining them in a rigid mutual relation completes the structure of the window platform.

In the operative association of the window platform with a window the corner defined by extensions 21 and the adjacent body portion of supporting arms 19 enters corner 15 defined by the adjacent edge of sill 12 and the upper end of wall 14. Clamping members 23 receive ledge 13. When 35 wing nuts 26 are driven against said clamping members 23 for shifting the same longitudinally of bars 10 and towards ledge 13, sill 12 will be clamped in a transverse relation by said clamping members 23 and extensions 21, thereby rigidly 40 locking the window platform to sill 12. This prevents any shifting movement of the platform either transversely or longitudinally with relation to sill 12. In this operative position of the window platform with relation to sill 12 the lower 45 portions of clamping member 23 and angle member 25 will be disposed below ledge 13, thereby preventing any angular movement of bars 10 or of the window platform with relation to sill 12, thereby 50 permitting supporting of the weight of a person while standing or sitting upon board 20.

By virtue of the fact that clamping members 23 are freely slidable upon bars 10 the window platform may be attached to windows having sills of various widths for clamping the latter between 55 said clamping members 23 and extensions 21.

Due to the fact that angle member 25 remains

in contact with the underface of ledge 13 through its entire length the load of the platform is distributed lengthwise of sill 12. Due to the rigid engagement of said angle member 25 with the free lower ends of said clamping members 23, said angle member 25 and said clamping members 23 constitute a unit which shifts in unison upon said bars 10.

While there is described herein preferred embodiments of the present invention, it is nevertheless to be understood that minor changes may be made therein without departing from the spirit and scope of the invention as claimed.

What I claim as new is:

A platform frame for a window sill having inner and outer edges, said platform comprising an inverted substantially U-shaped member forming a back for said platform, each of the arms of said member being bent substantially at right angles intermediate their respective ends to form a pair of platform supporting elements, said supporting elements extending away from said arms in the same direction and in a spaced parallel relationship, said supporting elements being bent at substantially right angles at a point adjacent their respective free ends to form abutment means for engagement with said outer edge of said window sill, said abutment means extending toward the base of said U-shaped member, a pair of substantially V-shaped braces, one end of each of

5 said braces being rigidly secured, respectively, with one of said arms at a point adjacent said base of said inverted U-shaped member, the apex of each of said braces being rigidly secured, respectively, to the end of its adjacent abutment means, the other arm of said braces being of sufficient length to extend transversely across said window sill, and a pair of U-shaped clamps for engagement around said inner edge of said window sill, means slidably securing each clamp, respectively, on said other arms of said braces, and means on each of said other arms of said braces engaging against the base of said U-shaped clamps and coacting therewith to clamp said 10 frame in operative position to said sill between said abutment means and said U-shaped clamps.

JOHN KOLODZIEJ.
